UNITED STATES PATENT OFFICE

AARON GROFF, OF ST. PAUL, MINNESOTA, ASSIGNOR TO GROFF PAPER COMPANY, OF ST. PAUL, MINNESOTA, A CORPORATION OF MINNESOTA

SANITARY CONTAINER FOR NAPKINS

Application filed March 6, 1926. Serial No. 92,717.

This invention relates to a container for folded napkins or similar articles. As is well known, paper napkins are now used in immense numbers in public and domestic eating places. It is customary to fold the napkins for distribution and to have them in this folded condition accessible to the users. If such napkins are placed in an open container, they quickly accumulate dust and dirt and become unsanitary. It is desirable, therefore, and required in some places, to have the napkins disposed in a closed container. It is also desirable to have such a container from which the napkins can be 15 quickly and easily removed one at a time. It is an object of this invention, therefore, to provide a container for folded paper napkins which is sanitary and simple in construction and which holds a napkin in position for easy removal.

It is a further object of the invention to provide such a container preferably shaped substantially to hold a napkin, which container has an opening at one side with means 25 adjacent the same for holding the napkins in position for easy removal, said container having means therein for moving the group of napkins toward said opening, and positioning them for removal one at a time.

It is another object of the invention to provide a dispensing container for folded napkins comprising a casing adapted to receive a group of said napkins, said casing having an opening at one side with flanges extending 35 along the sides thereof and over the edge of the folded napkin and means for pushing the group of napkins towards said flanges so that the endmost napkin engages said flanges adjacent said opening, said casing 40 also having means disposed inwardly of said flanges for engaging an edge of the folded napkin and adapted to cause one free edge of a napkin to project outwardly.

These and other objects and advantages of 45 the invention will be fully set forth in the following description made in connection with the accompanying drawings, in which like reference characters refer to similar parts throughout the several views and in 50 which:—

Fig. 1 is a view in front elevation of the device, certain parts being broken away and others shown in vertical section;

Fig. 2 is a vertical section taken on line 2—2 of Fig. 1 as indicated by the arrows;

Fig. 3 is a partial view in front elevation of the bottom portion of one side of the device;

Fig. 4 is a partial view similar to Fig. 2, shown on an enlarged scale;

Fig. 5 is a horizontal section taken on line 5—5 of Fig. 4 as indicated by the arrows;

Fig. 6 is a vertical section taken on line 6—6 of Fig. 4 as indicated by the arrows;

Fig. 7 is a horizontal section taken on line 65 7—7 of Fig. 1 as indicated by the arrows;

Fig. 8 is a view in front elevation showing a modified form of the device;

Fig. 9 is a vertical section taken on line 9—9 of Fig. 8 as indicated by the arrows;

Fig. 10 is a view in front elevation of a further modified form of the device;

Fig. 11 is a horizontal section taken on line 11—11 of Fig. 10 as indicated by the arrows; and

Fig. 12 is a view of a folded napkin such as used in the device.

Referring to the drawings, particularly Figures 1 to 7, a device is shown comprising a casing having the side portions 15 extending at an angle to each other and converging toward their upper ends. While these portions may be variously formed, in the embodiment of the invention illustrated, they are shown as formed from a thin plate bent 80 to form the sides 15 having the top portion 15a connecting said sides. The sides 15 have their front edges 15b bent substantially at a right angle to form the flanges 15b at one end of the casing. The flanges 15b as shown 85 in Fig. 1 meet at their top portions and then have their outer longitudinal edges diverging downwardly, the lower ends of said flanges curving to substantially no width. The angle between the sides 15 and the edges 90 of the flanges 15b is substantially the same as the angle between the sides and edges of a folded napkin so that the napkin N substantially fits in the casing. The end of the casing is open between the edges of flanges 15b. 95 100

The sides 15 have their outer edges 15c at one side thereof reversely curved to form grooves 15d for a purpose to be later described. Angle plates 21 are secured to the flanges 15b and have one of their sides 21a overlapping the sides 15 and spaced therefrom thus forming a groove or channel 15e between said angle bars and sides 15. The grooves 15e are thus alined with the grooves 15d and members 22 of sheet material can be disposed with their edges in each groove and lie against the outer surfaces of the sides 15. These members 22 may be cards having pictures or other ornamentation thereon, or cards having advertising matter thereon. Said cards preferably will be held in their proper position by small tongues or clips 22a secured at the bottom of sides 15 and substantially centrally thereof. The end of the casing opposite that having flanges 15b is formed by a removable plate 16 of substantially triangular shape, having a lower portion 16a reduced in width which fits in a recess 17 formed between the bottom 18 of the casing and a strip 19 which extends about and is secured to the sides of said bottom. The strip 19 is bent out at the one side of bottom 18 as shown at 19a to form the recess 17. The plate 16 has horizontal edges adjacent the ends of portion 16a which rest on the strip 19. The upper end of plate 16 is held in the rear of a catch 20 which catch has a vertical shoulder 20a adapted to engage the outer side of the plate 16. The catch 20 is formed on the end of top plate 20b of the casing which overlaps the top portion 15a of the plate forming the sides 15. The plate 20b is secured by the headed and nutted bolts 20c and is made of resilient material so the catch 20 can be lifted when desired. The plate 16 as shown in Fig. 5 has angles 21d at each side the flanges 21e of which overlap the portions 15c at the edges of sides 15. The plate 16 also carries at its lateral center and slightly below its vertical center, a coiled compression spring 23. Spring 23 as shown in Fig. 2 is conical in shape and has its smaller end secured to plate 16 by a headed and nutted bolt 23a. The larger and free end of spring 23 engages the rearmost one of the napkins N. A plate 24 is secured in the bottom member 18 and upstands therefrom a short distance, which plate is located a short distance inwardly of the plane of flanges 15b and the lower edge of the outermost napkins N, engages the plate 24. The bottom member 18 is secured to a plate 25, which plate has a depending stem 25a adapted to be received in a cylindrical hole in a base member 26 having a central flange on top of which plate 25 rests.

In operation the device will be disposed on a table or other suitable place where the napkins are to be dispensed. The plate 16 will be removed by lifting the catch 20 swinging

the top end of said plate outwardly then lifting said plate from the passage 17. The spring 23 is removed with said plate. A stock of napkins N are then placed in the container 70 is shown in Fig. 12 and said napkins will be placed with their ends N1 downward and resting on the bottom member 18. The plate 16 will now be again placed in position, its lower portion 16a being inserted in groove 17 and the top end swung inwardly until it snaps back of the shoulder 20a. The spring 23 will be somewhat compressed and will push the napkins toward the end of the casing having flanges 15b. The outermost napkin will be pushed against the flanges 15b and against the plate 24 at the bottom. Owing to the fact that plate 24 is disposed inwardly of flanges 15b the free folded over corner N2 of the napkin springs out as 80 shown in Fig. 2. When the user wishes a napkin, he needs simply take hold of the flap or portion N2 and withdraws the napkin from the container through the opening between flanges 15b. The napkin being of soft, flexible material, is easily withdrawn. When the napkin is so withdrawn, the spring 23 pushes the pack of napkins forwardly and the endmost napkin is immediately placed in position for removal. As stated, the cards 95 22 can readily be placed over the sides 15, which cards will carry ornamental or advertising matter. The casing containing the napkins can readily be revolved on the plate 25 so that napkins may be withdrawn from 100 various sides of a table.

In Fig. 8 a modified form of the device is shown, in which the casing comprising the sides 15, 16 and the bottom member 18, is disposed with its narrow end downwardly. The 105 casing is in all respects similar to that shown in Figs. 1 to 7 except that the top plate 20b will have a plate 27 secured thereto by the headed and nutted bolts 20c, which plate 27 will carry a stem 27a received in and revoluble in a bore in the base member 28. The plate 27 is of the same width as the sides 15 and as shown in Fig. 8 is slightly turned up at its outer end. The plate 24 shown in Figs. 1 and 2 will also be omitted and in place thereof a tongue 29 will be carried in the member 18 and will project downwardly over the top edge of the napkin a short distance inwardly of the plane of the flanges 15b.

In operation of the device shown in Fig. 8 110 the napkins will be inserted in the manner already described and the endmost napkin will be pushed forwardly against the flanges 15b. The member 29 engaging the top edge of the napkin causes the flap N2 to spring outwardly so that it can readily be engaged by the customer and the napkin pulled from the casing. The plate 27 is provided to carry some usual table accessory such as a salt or pepper shaker.

In Fig. 10 a further modified form of the device is shown adapted to contain napkins in which the portion N2 is not folded over on the other portions but is left projecting as indicated by the dotted lines Nc in Fig. 12.

5 The casing will be formed as described in connection with Figs. 1 to 7 except that instead of the flanges 15b, flanges 30 and 31 will be provided, the latter of which is of shorter length, leaving a portion of the casing open at its side. Flanges 32 will also be provided extending along the top side of the casing, it being noted that the casing is shaped substantially to fit the shape of the napkin used.

10 15 A plate 33 is disposed between the ends of flange 32 and flange 31, which plate as shown in Fig. 11 is disposed somewhat inwardly of the plane of flanges 30, 31 and 32.

In operation the napkins will be placed in 20 the casing as already described and will be pushed forwardly by the spring 34 against the flanges 30, 31 and 32 and one edge of the napkins will be engaged by the plate 33. This plate being somewhat inwardly of flange 31 25 and just above the corner of one of the folded over side portions of a napkin, said corner will tend to spring outwardly and this corner may readily be engaged by the user to withdraw the napkin from the casing. It is not necessary, however, for the customer to take 30 hold of said corner as he can readily take hold of the napkin by placing his finger within the top edges Na of the folded over side portions of a napkin, both of these side portions in Fig. 10 being shown as folded inwardly at the same side of the napkin. The form of napkin used in Fig. 10 is now quite 35 commonly used and is generally referred to as the V-shaped fold. The napkins are usually square and are first folded successively along their central lines into quarter fold shape. They are then folded along lines passing through one corner of the quarter fold and inclined at about 30 degrees to 40 the adjacent side of the napkin, thus giving the folded shape shown in Fig. 10.

From the above description it is seen that 45 applicant has provided a very simple, efficient and sanitary container for folded napkins or similar articles. The casing is quite simple in construction and easily made from 50 simple materials. The napkins are substantially covered and protected from dust and dirt. The device always presents one napkin in position to be easily and quickly removed and it will be noted that only one napkin will be removed at a time. Where the 55 folded napkins are placed in an open top container, the user often withdraws two or more napkins at a time, thus causing unnecessary waste. In the present device only one napkin will be engaged and withdrawn. The 60 device is of a size to be conveniently placed in the center of a lunch or dining table such as used in restaurants or placed on a lunch

counter where the patrons may quickly secure the napkins. The device has been amply demonstrated in actual practice and found to be very successful and efficient.

It will, of course, be understood that various changes may be made in the form, details, proportions and arrangement of the parts, without departing from the scope of applicant's invention, which, generally stated, consists in a device capable of carrying out the objects above set forth, in the novel parts and combinations of parts disclosed and defined in the appended claims.

What is claimed is:

1. A container for holding napkins which have been folded into four-ply quarter-fold shape and then had triangular side portions folded over on the central portion to form a V-shaped article, and then had the corner thereof folded inwardly to form a triangular-shaped article, having in combination, a base, a container of triangular shape in cross section having sides inclined to the vertical and being disposed substantially at the same angle as that between the edges of said folded napkins, said casing having a side disposed parallel to the flat side of said folded napkins and having an open front end with flanges projecting inwardly from the inclined sides thereof extending a short distance beyond the edges of said napkin, means engaging said napkins at the side extending between said inclined sides, said means being disposed inwardly of the plane of said flanges and means pushing said napkins toward said last mentioned means engaging one of said napkins over a comparatively small area and out of horizontal alignment with said means whereby the napkins are flexed adjacent said first mentioned means and the folded over corner of the endmost napkin is projected forwardly at said open end and may be readily engaged to withdraw the endmost napkin.

2. A container for holding napkins which have been folded into four-ply quarter-fold shape, then had triangular side portions folded over onto the central portion to form a V-shaped article and then had the corner at one end of said article folded inwardly to form a triangular shaped article having in combination, a base, a container of triangular shape in vertical cross section having sides extending upwardly from said base and disposed substantially at the same angle as that between the long edges of said article, one side of said container being substantially horizontal and parallel to the short edge of said triangular shaped article, said container having an end which can be removed to place articles in said container and having an open end with flanges projecting inwardly from the upwardly extending edges thereof and extending a short distance over the endmost napkin disposed in said container, a lug at the horizontal edge of said open end pro-

jecting toward the opening therein and having a portion disposed quite a distance inwardly of the plane of said flanges for engaging the short side of said triangular shaped article and means pushing said articles toward said open end disposed out of horizontal alignment with said lugs thus flexing said articles adjacent said lug and causing said corner of the endmost napkin 10 to spring forwardly at the open end of said container whereby the same may be engaged to withdraw said endmost napkin.

In testimony whereof I affix my signature.
AARON GROFF.
